DRAFT KEY RETAINING DEVICE

Filed July 26, 1926

2 Sheets-Sheet 2

UNITED STATES PATENT OFFICE.

AUGUST W. L. HARTBAUER, OF CHICAGO, ILLINOIS.

DRAFT-KEY-RETAINING DEVICE.

Application filed July 26, 1926. Serial No. 125,981.

This invention relates to a draft rigging, such as used on railway rolling stock and particularly to a means for retaining the draft keys used with such draft rigging. 5 Such a draft rigging in modern railway structures comprises a coupler extending into the center sills at the end of a railway car, said coupler being connected to a draft yoke. A heavy key passes through the sill casing 10 and through openings in the coupler and yoke, thus connecting the latter together. It has heretofore been a common practice to have a retaining means for these draft keys, comprising a cotter pin extending through a 15 vertical hole in the draft key at the exterior of the sills.

It is an object of this invention, therefore, to provide a simple and efficient draft key retaining means mounted on the sills adapted 20 normally to hold the key in position, but being capable of being moved out of alignment with the key so that the key can be readily withdrawn when desired.

It is a further object of the invention to 25 provide a draft key retaining means comprising a member pivoted to the exterior of sills adapted normally to lie in front of a key but swingable out of alignment with the key.

30 It is still another object of the invention to provide a draft key retaining means comprising a yoke pivoted at its ends to the sill and normally held in desired position by a bracket also secured to the sill.

35 These and other objects and advantages of the invention will be fully set forth in the following description made in connection with the accompanying drawings, in which like reference characters refer to the same parts throughout the different views and in which:

Fig. 1 is a view in side elevation of the front end of a draft rigging showing the invention applied thereto;

45 Fig. 2 is a view in horizontal section taken substantially on line 2—2 of Fig. 1 as indicated by the arrows;

Fig. 3 is a view in vertical section taken 50 on line 3—3 of Fig. 1, as indicated by the arrows;

Fig. 4 is a view in side elevation of the front end of the sill showing a modified form of the invention, and

Fig. 5 is a top plan view of Fig. 4.

Referring to the drawings, particularly Figs. 1 to 3, a portion of the front end of

the draft rigging for a railway car is shown, comprising the side sills 6 which, in the embodiment of the invention illustrated, is shown as a channel member having its flanges 60 directed outwardly. The end member of the sill is shown as 7, which member has a flange 7^a extending at the outer side of the web of sill 6 and riveted thereto as shown by the rivets 8, the flanges 6^a being cut away 65 at the forward end of sill 6 to accommodate the flange 7^a. The member 7 also has spaced lugs 7^b extending rearwardly from flange 7^a and also riveted to the web of sill 6. A portion of the yoke disposed within the sill is 70 shown in Fig. 2 in dotted lines as 9 and the outer side of the coupler which is connected to the yoke 9 is indicated in dotted lines as 10. A guide plate 11 is disposed at the inner side of the sill 6, being riveted thereto as 75 shown in Figs. 1 and 2, by the rivets 12. The coupler 10 and the yoke 9 have slots extending transversely therethrough and a draft key 13 extends through the slots and forms a connecting means for the coupler and yoke. 80 The key 13 also extends through a slot 6^c in the side of the sill 6 and said key is in the embodiment of the invention illustrated, shown as having a head 13^a thereon. A pair of sill locating and securing angles are shown 85 as 14 in Fig. 1 which extend transversely of the draft rigging.

In accordance with the present invention, member 7 is provided with an outwardly extending flange 7^c and a bracket 15 is secured 90 to the outer side of sill 6, spaced some distance from the flange 7^c, said bracket 15 having spaced lugs 15^a secured to sill 6 by a pair of rivets 12. The bracket 15 has an outwardly extending flange 15^b and this 95 flange and flange 7^c are provided with aligned holes having a common horizontal axis, which holes receive the trunnions 16^c projecting at each end of a member or yoke shaped bracket 16 which is thus pivotally mounted about a 100 horizontal axis in bracket 15 and flange 7^c. The yoke 16 is U shaped in plan, having a central projecting re-inforcing rib 16^b on its outer side. Bracket 15 is provided with a short flange 15^c at its bottom, projecting 105 toward flange 7^c and the bottom of the yoke 16 at one end rests on flange 15^c, the yoke thus being held in normal position. As shown in Figs. 1 and 3 the outer side of yoke 16 is disposed in alignment with the head 13^a 110 of the key 13 and in close proximity to the outer side of said head. The yoke 16 as

shown in Fig. 3 can be swung upwardly about the trunnions 16^a out of alignment with key 13, so that the said key may then be drawn outwardly, as shown in dotted lines in Fig. 3.

In normal operation the parts will occupy the position shown in full lines in Figs. 1 to 3. The yoke 16 will be retained in its position on flange 15^c by gravity and will thus be disposed directly in front of key 13, so that any excessive endwise movement of this key outwardly is prevented. If it is desired to remove or insert the key, yoke 16 is swung upwardly out of the way and the key can thus be drawn out or inserted endwise. Inward movement of the key 13 is limited by the head 13^a which cannot pass through the slots 6^c in the sill 6. While the yoke illustrated in Fig. 2 is of the form commonly called a vertical yoke, having a single key therein, it will be apparent that the structure would serve equally well with the horizontal type of yoke.

In Figs. 4 and 5 the invention is shown applied to the horizontal type of yoke and to a coupler and yoke having two draft keys therein. In these figures the side sill is shown as 20, the same being formed of standard channel, having the top and bottom flanges 20^a. The end sill plate is shown as 21, secured to the inner sides of the sill 20 and the carrier plate 22 is shown at the bottom of sill 20 at the front thereof. The usual cheek plate 23 is secured to the outer side of the sill 20, which plate, together with the sill, has elongated slots 23^a extending therethrough. A portion of the yoke of the draft rigging is shown at 24 which is connected to the coupler 25, a portion of which is shown in dotted lines in Fig. 5. The yoke 24 and coupler 25 have slots therethrough, through which pass the connecting draft keys 26, the draft rigging illustrated being of the double key type. Keys 26 project outward through the sill and cheek plates 23 and are provided with heads 26^a at their outer ends outward of said cheek plates, which heads are similar in shape to those shown for the key 13 in Figs. 2 and 3. An angle shaped bracket 27 is secured at the forward end of the cheek plate 23 and by one of the rivets 20^a which connects the cheek plate to the sill, said bracket having an outwardly extending flange 27^a and a horizontally extending flange 27^b at its lower side. Another angle shaped bracket 29 is secured adjacent the other end of the cheek plate 23 by one of the rivets 20^a which connect the cheek plate to the sill. Bracket 29 has an outwardly projecting flange 29^a and this flange and flange 27^a are provided with holes disposed about a common horizontal axis. A yoke shaped bracket or member 30 has trunnions 30^a projecting at each end pivotally mounted in the holes in flanges 27^a and

29^a. Yoke 30 is U shaped in plan and has a re-inforcing rib 30^b projecting outwardly therefrom at its front side. As shown in Fig. 4 the outer side of the yoke is in alignment with the heads 26^a of the keys 26. 70 The yoke 30 is normally positioned with its lower side resting on the flange 27^b and said yoke can be swung upwardly about its trunnions so as to be out of alignment with heads 26^a of keys 26. 75

In operation the yoke 30 normally rests on flange 27^b of bracket 27 and is held in this position by gravity. Excessive outward movement of the keys 26 is thus prevented, as the keys will contact the inside of the yoke 30 and be held from any further movement. The keys are also held from any movement inwardly by the heads 26^a engaging the outer side of the cheek plate 23. The keys therefore cannot work out endwise, and 85 cause trouble. When it is desired to remove or replace the keys, the yoke 30 can be swung upwardly and the keys can thus be drawn out of or inserted through the slots in the sill 20, cheek plate 23 and in the yoke and 90 coupler.

From the above description it will be seen that applicant has provided a very simple and effective key retaining means. The parts are permanently carried on the sill 95 and are normally in key retaining position. It is a simple and easy matter to remove and insert the keys. The device is quite easily and inexpensively made and installed on a 100 car. The same has been amply demonstrated and found to be very successful and efficient.

It will, of course, be understood that various changes can be made in the form, details, arrangement and proportions of parts, 105 without departing from the scope of applicant's invention, which, generally stated, consists in a device capable of carrying out the objects above set forth such as shown and described and defined in the appended 110 claims.

What is claimed is:

1. A draft rigging comprising a sill, a yoke, a coupler, a key connecting said yoke and coupler and having a yoke pivotally connected to said sill and normally disposed in front of said key and means carried by said sill for holding said yoke in key retaining position, said yoke being swingable to permit removal of said key. 115

2. A draft rigging comprising a sill, a yoke, a coupler, a key connecting said yoke and coupler and projecting through said sill, brackets carried by said sill, a member pivotally mounted in said brackets about a 125 horizontal axis extending longitudinally of said sill and disposed in front of said key to prevent excessive endwise movement thereof, and means carried by one of said brackets on which said member rests. 130

3. A draft rigging comprising a sill, a yoke, a coupler, a draft key connecting said yoke and coupler and projecting through said sill, said key having a head thereon disposed outward of said sill and preventing inward movement of said key, and means swingable about a horizontal axis tending longitudinally of said sill normally disposed in front of said key, preventing outward movement of said key but swingable upwardly to a position out of alignment with said key to permit withdrawal of said key.

4. A draft rigging comprising a sill, a

yoke, a coupler, a draft key connecting said yoke and coupler and projecting through said sill, spaced apertured brackets at each end of said key carried by said sill, a yoke having trunnions at its ends respectively journaled in said brackets, means supporting said yoke in position in front of said key so as to prevent lengthwise movement thereof, said yoke being swingable upwardly to permit removal of said key.

In testimony whereof I affix my signature.

AUGUST W. L. HARTBAUER.
